UNITED STATES PATENT OFFICE.

SHADE WESLEY TURNER AND THOMAS HARBER, OF WALLINS CREEK, KENTUCKY.

CURTAIN FASTENING AND RELEASING MEANS.

Application filed January 23, 1925. Serial No. 4,206.

To all whom it may concern:

Be it known that we, SHADE WESLEY TURNER and THOMAS HARBER, citizens of the United States, residing at Wallins Creek, 5 in the county of Harlan and State of Kentucky, have invented certain new and useful Improvements in Curtain Fastening and Releasing Means; and we do declare the following to be a full, clear, and exact 10 description of the invention such as will enable others skilled in the art to which it appertains to make and use the same.

Our invention relates to improvements in fastening and releasing means for curtains, 15 and the invention further relates to pendant curtains whose lower edges are disposed adjacent swinging doors, for connection therewith, the primary use of such invention being upon automobile and other 20 vehicle bodies, such as the bodies of touring cars and roadsters. In order to open the doors of automobile bodies of these types, when the curtains are in use, it is customary to first unfasten at least the lower edge of 25 a curtain or curtains, which is often very inconvenient as the driver usually has to reach to the exterior of the machine to release the fastening means. It is the object of our invention however, to provide a simple 30 and very desirable arrangement of parts, whereby the fastening means for the lower edge of the curtain above any door, is automatically released by releasing the latch of said door, preparatory to opening the latter.

With the foregoing in view, the invention resides in the novel subject matter herein-after described and claimed, the description being supplemented by the accompanying drawing.

Figure 1 is a fragmentary side elevation showing the association of our invention with a door and a pendant curtain whose lower edge is disposed adjacent said door.

Figure 2 is an enlarged vertical sectional view as indicated by line 2—2 of Fig. 1.

Figure 3 is a view similar to Fig. 2, but illustrating the manner in which the curtain is released.

In the drawing above briefly described, the 50 numeral 1 designates a portion of an automobile door, and 2 indicates in a general way, the usual or any preferred form of latch for said door, said latch having an operating handle 3 which, in the present instance, is 55 rotatable with a short shaft 4, for the purpose of releasing the latch.

5 designates a pendant curtain which is hung from the top of the automobile in the usual or any preferred manner, the lower edge of said curtain overlapping the door 60 and being preferably provided with an appropriate stiffener 6. This curtain is equipped with an appropriate eye or the like 7 which normally receives the outer end of a bolt 8 which is slidably and rotatably carried by the door 1, an arched frame 9 being shown within the door, for supporting said bolt. Preferably, the outer end of the bolt 8 is formed with a notch 10 to engage the member 7, and said end may well be beveled 70 as indicated at 11 to facilitate its engagement with said member 7. We provide means for rotating the bolt 8 when the handle 3 is turned to release the latch 2, and means are also employed whereby when rotation of 75 said bolt is effected, it will be longitudinally shifted and withdrawn from the member 7, thereby releasing the curtain 5. In the present showing, there is a sprocket 12 on the bolt 8 and another sprocket 13 on the 80 shaft 4, the two sprockets being connected by a sprocket chain 14 and being of any desired sizes, so as to utilize the relatively small movement of the handle for rotating the bolt to a greater extent. In the construction illustrated, the bolt 8 is provided 85 with an enlargement 15 having a pitched cam groove 16 which receives a projecting pin or other shoe 17 carried by the door, this pin or shoe being preferably mounted on 90 the crown portion of the arched frame 9.

By providing the construction shown and described, turning of the handle 3 to release the latch 2, will cause the sprocket 13 and sprocket chain 14 to rotate the sprocket 12, 95 thus rotating the bolt 8 and causing the co-acting cam groove 16 and shoe 17, to slide said bolt inwardly, thus automatically disengaging it from the fastening member 7 of the curtain 5 so that the lower end of the latter is freed, permitting the door 1 to be readily opened. When the door is again closed and the latch is fully engaged with the keeper, the bolt 8 again projects in position for use, as will be readily understood.

By providing the unique association herein shown or a substantial equivalent thereof, it will be seen that a distinct improvement is made over the ordinary methods of fastening the lower ends of vehicle and analogous 110 curtains, and as excellent results may be obtained from the general construction shown,

it may of course be followed. However, within the scope of the invention as claimed, modifications may of course be made.

We claim:

- 5 1. In combination, a door having a latch provided with an operating handle, a pendant curtain hung independently of the door and having its lower edge disposed adjacent said door, means for fastening the curtain to the door, and releasing means for said fastening means operatively connected with a portion of said latch to be actuated thereby, whereby to release the curtain fastening means when the latch is released to open the door.
- 10 2. In combination, a door having a latch provided with an operating handle, a pendant curtain hung independently of the door and having its lower edge disposed adjacent said door, a door-carried bolt projecting normally from the door into engagement with the curtain, and means operatively connected with a portion of the door latch and said bolt for withdrawing the latter from the curtain when the latch is released to open the door.
- 15 3. In combination, a door having a latch provided with an operating handle, a pendant curtain hung independently of the door and having its lower edge disposed adjacent

said door, a bolt rotatably and slidably carried by the door and normally projecting therefrom into engagement with the curtain, connecting means between the bolt and a portion of the door latch for rotating the bolt when the latch is released to open the door, and means operatively associated with the bolt for automatically withdrawing the latter from the curtain when said rotation is effected.

4. In combination, a door having a latch provided with an operating handle, a pendant curtain hung independently of the door and having its lower edge disposed adjacent said door, a bolt rotatably and slidably carried by the door and normally projecting therefrom into engagement with the curtain, connecting means between the bolt and a portion of the door latch for rotating the bolt when the latch is released to open the door, said bolt having a pitched peripheral cam, and a stationary shoe carried by the door and engaging said cam to withdraw said bolt from the curtain when the aforesaid rotation of the bolt is effected.

In testimony whereof we have hereunto affixed our signatures.

SHADE WESLEY TURNER.
THOMAS HARBER.
